UNITED STATES PATENT OFFICE.

CHARLES H. EVANS, OF NEW YORK, N. Y., ASSIGNOR OF ONE-HALF TO
DANIEL H. CRAIG, AGENT, OF SAME PLACE.

ABSORPTION ICE-MACHINE.

SPECIFICATION forming part of Letters Patent No. 318,971, dated June 2, 1885.

Application filed September 19, 1884. (No model.)

To all whom it may concern:

Be it known that I, CHARLES H. EVANS, a citizen of the United States, residing at New York, in the county and State of New York, have invented new and useful Improvements 5 in Absorption Ice-Machines, of which the following is a specification.

My invention relates to that class of ice-making or refrigerating machines in which the alternate expansions and condensations of ammoniacal or other equivalent gases produce the refrigerating effects. In such machines as hitherto constructed there was liability to what is ordinarily known as "boiling over," 15 and the joints or couplings in such machines were liable to leakage, and were not readily interchangeable or repairable. In my improved construction I provide a by-pass or side path from the still through the dome or stand-pipe for the gas, so that the gas eliminated from the ordinary waters may be passed to the condenser without having to force its way through the body of the ammoniacal water used as the refrigerating agent, and all 20 sections or joints of the pipes where connections are made are in view for inspection, so that any leakages may be readily determined, and the necessary repairs made without dismemberment of the entire apparatus, and 25 whereby what has been noted as "boiling over" is guarded against.

To these ends my invention consists in a peculiar construction of the parts, as herein-after noted, and in the particular combination 35 of parts, as hereinafter described.

In the drawings hereunto annexed there is shown a machine embodying my invention.

In the drawings, Figures 1 and 1^a represent a view, partly in section and partly in elevation, of the entire ice-making or refrigerating machine, Fig. 1 being a view of one half thereof, while Fig. 1^a is a view of the other half thereof. Fig. 2 is a view, partly in plan and partly in section, of my improved 45 ammonia-still or gas-generator, including what I hereinafter term the "interceptor." Fig. 3 shows partly in plan and partly in section my devices for forming connections between the pipes used in the interceptor, the still, the 50 condenser, and the absorber, while Fig. 4 is

a plan view of the concentric pipes and headings or unions therefor. Fig. 5 represents in perspective, with the exterior casing broken away, the dome or stand-pipe which I prefer to use, and the arrangement of "baffle" or 55 check plates used therein.

In the drawings, 1 represents the pump used to force the supply of ammoniacal or other refrigerating agent through the system of pipes. The pipe for this purpose is shown at 2, 60 which passes to and through what I call the "interceptor," it being surrounded at 13 with concentric pipes, affording a path and exit for the gases eliminated in the still and dome from the ammoniacal waters passed therethrough. 65 This pipe 2 communicates, as shown, with a dome or stand-pipe, 5, interposed between this inlet-pipe, forming the interceptor and the still proper. This dome or stand-pipe is constructed with retarding or baffle plates 6, downwardly-inclined, and attached alternately to opposite sides of the dome or stand-pipe, so that the liquid forced therethrough shall be broken up and forced to pass therethrough in a fine sheet or spray. From thence this am- 70 moniacal fluid passes to the still 7, consisting of a series of pipes passing alternately back and forth. Each pipe of still 7 is surrounded by a steam-pipe, 59, the pipes of 7 being concentrically seated therein, so as to form a space 75 through which steam or other heating agent may be passed to vaporize and send off in gaseous form the ammonia or ammoniacal gas of the liquid.

To supply the necessary heat evenly and 80 equitably to all the coils of this still, a steam stand-pipe, 44, is used, from which branches 45 are formed, leading to each member of the coil of the still, so that each member of the coil is subjected to the same degree of heat 85 and pressure. At the other end of these members of the coil a return-pipe, 46, is provided, into which lead return-pipes 47 from the coils of the still. This pipe 46 has placed in its circuit a steam-trap, 48, from whence it may 90 lead back to the boiler or other desired point. By this arrangement all the coils of the still are subjected, as before stated, to equal heat and pressure, whereby the more thorough 95 elimination of the gas from its fluid vehicle is 100

insured, all the coils of the still, so to speak, being in multiple arc instead of in series, as hitherto practiced.

The still is formed of a series of parallel pipes or tubes connected at alternate ends by the elbows or return-pipes 9, more particularly hereinafter described. These return-pipes or elbows are formed with check or baffle plates 8 upon their interior, so as to keep the horizontal portions of the coils of the still about one-half full of the liquid from which the gas is to be eliminated. Hitherto in apparatus of this kind the eliminated gas to be used on its condensation and expansion 15 as the refrigerating agent has been compelled to traverse in the still the entire body of incoming ammoniacal water, and if at any point such ammoniacal water was below the point of saturation the liberated gas was simply absorbed thereby. In order to prevent such sequence of action and deliver the eliminated gas at a point beyond the inlet of any weakened ammoniacal water, there is provided from the alternate elbows or unions of 20 the coils of the still a series of pipes, which may be called a "by-pass" or "shunt," conducting the freed gas from each coil of the still entirely around the still. The main pipe of this by-path or shunt is shown at 11, whose 25 inner end connects with the base of the dome or stand-pipe 5, branch pipes 10 connecting the upper member of each coil of the still with such pipe 11 in the neighborhood of the upper portion of such member and of the baffle or check plate 8. The result of this construction is that the heated eliminated gas is conducted directly to the dome or stand-pipe, where it meets the incoming strong ammoniacal liquor passing over the check or baffle 30 plates 6 and is cooled thereby, while this liquor is heated by its contact with the gas. At the top of the dome or stand-pipe is a pipe, 12, which leads into the space formed by the pipes or tubes 13, concentrically surrounding the inlet 2. While in the drawings but two 35 coils of this inlet-pipe 2 and surrounding gas-exit pipe 13 are shown, it is to be understood that any desired number thereof may be used. This construction forms what I call in this 40 class of machines the "interceptor," in which the liberated gas, heated in its liberation, passes around on its way to the condenser, the tubes bringing in the cold gaseous liquor, whereby the gas is cooled to a considerable degree on its passage to the condenser, and the inflowing liquor is heated to a considerable degree before it reaches the dome or stand-pipe and the still. Thus economy of fuel is 45 insured, and the hot gas and the cold liquor are made to act on each other, and each brought to an average temperature best suited for the subsequent operations thereon. By the pipe 12, provided with a suitable stop-cock to regulate its flow, as shown, the eliminated gas 50 passes within tube 13 and around tube 2 by means of cross-connections 14 to the tube 15 of the condenser. These tubes 15 are seated

concentrically within tubes 30, whereby a water or cooling space is formed around them, which is kept supplied with cold water or 55 other cooling liquid by the pump 27. In these pipes 15 the freed or eliminated gas is cooled and condensed, from whence it passes by pipe 16, provided, when desired, with the cock or valve 17, to the receiver 18. This receiver is provided with the ordinary visual 60 gage, 20, connected thereto by pipes 19, 19, in order that the amount of condensed or liquefied gas may be readily determined.

21, connected with the receiver 18 by pipes 85 62 64, in which may be placed one or more stop cocks or valves, 60, is the manifold expander, from whence lead any desired number of connections to refrigerating-coils 21. In the drawings but one such refrigerating-coil, 85 with its appropriate stop-cocks or check-valve, is shown; but it is to be understood that any desired number may be connected thereto, a series of such connections, 65, being shown. The gas, having expanded in this manifold expander and the refrigerating-coils connected therewith, and in such expansion having abstracted a percentage of the heat from the surrounding objects, passes to the return manifold 22, whence, by pipe 23, it is conducted to 90 the absorber composed of tubes 24. The ammoniacal liquor from whence this gas was eliminated in the still passes from the lower member thereof by pipe 36, provided with a suitable cock or check-valve, into chamber 78, 95 whence it passes by pipe 34 to pipe 38, surrounding inlet-pipe 2. From this pipe 38, by connection 39, it passes to pipe 40, of any desired number of convolutions, surrounded by cooling-pipe 33, so as to reduce its temperature to its normal point. Thence, by pipe 41, this weakened and cooled liquor is passed to pipe 24 of the absorber, meeting the gas hitherto freed from it at point 42. This weakened liquor and gas are then forced through the 100 pipes 24, which are of such extent that the gas is again absorbed by the water, and the liquor, now revivified, is passed by the pipe 25 to the receiver or tank 26, from whence it may be again forced by the pump 1 through 105 the same series of operations.

The system of cold-water circulation used to cool the gases and liquids in the condenser, absorber, and weak-water pipes is supplied and controlled by the water-pump 27, from 110 which leads water-outlet pipe 28. This pipe extends to any desired distance or point, and is provided with any suitable number of branches for conveying the cooling-water to the desired points. In the drawings one such 115 branch, 29, is shown as typical of any number which may be used, 29 connecting by branches 79 79 with both the condenser and the absorber. The branch 79, connecting with the condenser, delivers the water into the space formed 120 between the concentric tubes 15 and 30, cooling and condensing 15 and the ammoniacal gases passing therethrough. After circulating around the pipes of the condenser the wa-

ter passes by pipe 49 to the space between the concentric tubes 40 and 33, which form what I term the "weak-water system"—that is, the system of pipes in which the spent liquor, or liquor from which the gas has been largely eliminated, is still further cooled preparatory to being passed into the absorber-pipes 24. After passing around these pipes this water finds exit by branch 43 to the tubes in chamber 78, whence it is permitted to escape. The other branch 79 from 29 delivers water in the space between the concentric tubes 24 and 31 of the absorber, from which, after circulating therearound, it passes to a waste-pipe or to connections for other uses at the point 80. This description as thus far given gives, generally, the construction of the entire machine and its mode of operation, embracing the elimination of the gas from its fluid vehicle or carrier, the cooling and condensation of the gas, its expansion in the refrigerating coils or chambers, and its reabsorption by the water from which it was before eliminated, which sequence of operations are repeated, the same liquor and gas being used over and over. In order, however, to render the apparatus still more perfect, I have invented and embodied it in certain other details of construction, which will be more particularly referred to and described.

As hitherto constructed, it has been found that the joints of the ammonia-pipes were apt to leak. If such a thing occurs, it is desirable that it be immediately known. If not discovered at once, the leakage may continue without discovery until all of the gas (the active agent for the result desired) has escaped, involving serious loss both in time and money. To avoid this I arrange a peculiarly-constructed junction having little liability to leakage, and also arrange all the joints in sight, so that if perchance any leakage should occur it would be immediately discovered. At the same time in such joints or couplings are arranged all the connections for the pipes they serve or are attached to, so that any tapping and consequent weakening of the pipes is avoided; and, furthermore, these junctions or unions are so made that in case of injury to any section of pipe such section may be readily removed without disturbance of the remainder of the apparatus and a new section inserted, the only loss entailed being a few minutes stoppage of the machine.

All the return-connections between the interior pipes composing any portion of the apparatus are made by the elbows or return-bends 9, each end thereof being formed with a flange, 50. The ends of these interior pipes themselves—as, for instance, the pipes 7 or 15 or 24—are screw-threaded and secured by these screw-threads in disks 51, which then form flanges to the pipes 50 and 51, are then secured together by bolts, any suitable packing being interposed, if desired. The exterior or surrounding pipes, as 24, 30, 33, or 59,

are tapped into a thimble, 52, provided on its interior with an inwardly-projecting flange, 75, adapted to inclose quite snugly the interior pipe. A gland or thimble, 56, having a projection, 76, about at a right angle to its body, adapted to inclose and lie parallel to the interior pipe or tube, is used. Its projecting portion is adapted to enter the chamber formed in the interior of thimble 52, and about or nearly about on the flange 75. The thimble 52 being secured to the exterior pipe and the interior placed in position therein, any suitable washing or packing is placed around the interior pipe, when the gland or thimble 56 is placed in position, and it and 52 brought firmly together by bolts passing through the flange of 56 into the body of 52, compressing the packing and forming a tight joint for the exterior pipe and for it around the interior pipe. All of the openings for connections from the pipes and the connections themselves are made in these thimbles. For instance, in Fig. 3, is shown in each thimble 52 a connection, 54, provided with flange 55. These connections 54, being united by bolting through the flange 55, form a passage from the members of the outside system of pipes to each other. At the terminals of a system of pipes, instead of an elbow, 9, a head, 72, having flanges 71 is used, to which is attached, and with which is formed, the flanged projecting pipe 73. This construction obviates any tapping and consequent weakening of the wrought pipes. From this it may also be seen that any section upon the removal of the bolts uniting the flanges 50 51 at its ends may be readily removed and replaced immediately by a new section. At the same time all the joints 50 51 subject to the action of the ammonia are in sight and position for constant care and inspection. Where these elbows 9 are used for the still, they are to be cast or formed with the interior check or baffle plates, 8, so as to insure the presence of a large amount of the ammoniacal liquor constantly in the still.

The use of the by-pass or shunt-route and of the interceptor aids in equalizing the pressure throughout the entire apparatus, which is further and completely accomplished by the peculiar course which the liquor and eliminated gas take. It will be noticed that as the gas is abstracted from the liquor, the gas and the liquor travel in opposite directions and unobstructed until they unite again in the absorber, whence they flow to the receiver, to be started again on their path through the machine. At the same time, by the use of the by-pass and the interceptor, the outflowing eliminated gas and the incoming liquor are caused to react on each other, one cooling the other and being heated in turn thereby, by which more thorough utilization of fuel and great economy in its consumption are accomplished.

The dome or stand-pipe 5 is provided with an air-blow-off pipe, 57, with suitable valve or

cock, 58, the opening of which permits the escape of any air which may be in the machine at its starting.

The construction of details and the combinations thus set forth produce a machine exceedingly economical in first cost, and in consumption of material in use, reliable in action, durable, and not liable to derangement, and in which danger of accident is reduced to a minimum.

It should be noted that in passing out of the still a certain percentage of steam or watery vapor is commingled with the ammoniacal gas set free from the fluid-vehicle. It is of great importance that this steam or watery vapor shall be wholly condensed and separated from the gas, leaving the latter essentially pure and dry. One of the main functions of the interceptor hereinbefore described is to accomplish this result. As the liberated gas passes over and around the still in which it has been set free from its vehicle, it passes, together with the commingled vapor, into the stand-pipe, and is driven up through the pipe 12 in- 25 to the outer concentric pipe of the interceptor and around the inlet-pipe 2, containing the cold ammoniacal liquor passing to the stand-pipe. The contact of the mingled gas and steam with the cold inlet-pipe not only raises 30 the temperature of the latter, but so far lowers the temperature of the gas as to condense out of it the steam and water vapor, which returns down the dome or stand-pipe to the still, leaving the gas essentially pure and dry. This 35 reciprocal heating and cooling is carried on equally at every point of the coils of the interceptor, the cold ammoniacal liquor passing one way, while the gas passes in the opposite direction.

40 It will be seen from the foregoing and by an inspection of the drawings that the several parts of the machine are in sections, whereby it can be taken apart at any time—as, for example, when the season terminates—so that 45 the water-cooling and ammonia pipes can be removed and cleaned from corrosion, thus making the machine more durable.

Having thus described my invention, what I claim, and desire to secure by Letters Patent, 50 is—

1. In an ice-making or refrigerating machine, an interceptor interposed between the inlet-pipe and the still, the cold ammoniacal liquor and the gas liberated by the still passing 55 through said interceptor and exercising a reciprocal heating and cooling action, whereby the steam and watery vapor is condensed out of the gas and returned to the still, substantially as described.

60 2. In an ice-making or refrigerating machine, the combination, with the inlet-pipe and the still, of an interposed interceptor through which the cold ammoniacal liquor flowing to and the gas liberated by the still 65 pass in opposite directions, whereby a reciprocal heating and cooling is effected, raising the temperature of the inflowing liquor and

condensing the steam and watery vapor out of the gas and returning said condensed fluid to the still, substantially as described. 70

3. In an ice-making or refrigerating machine, an interceptor consisting of concentric pipes or tubes, through one of which passes the gaseous liquor to the still, the liberated gas passing through the other, the incoming 75 liquor and outflowing gas passing in opposite directions for mutual action upon each other as to cooling and heating, substantially as set forth.

4. In an ice-making or refrigerating machine, a dome or stand-pipe interposed between the supply-reservoir and the still, consisting of an exterior casing and interior downwardly-projecting baffle or check plates alternately attached to and projecting from two 85 opposite sides of the exterior casing, substantially as set forth.

5. In an ice-making or refrigerating machine, the combination, with the pipes forming the still, of internally and upwardly projecting check or baffle plates, whereby chambers for retaining the liquor are formed, substantially as set forth. 90

6. In an ice-making or refrigerating machine, the combination, with the pipes forming the still, of a series of pipes connected thereto and forming a by-pass or shunt-path for the liberated gas around the still, substantially as set forth. 95

7. In an ice-making or refrigerating machine, the combination of a supply reservoir or tank, a stand-pipe or dome, a still, and an interceptor for heating the incoming liquor, interposed between the supply-reservoir and the dome or still, substantially as set forth. 100

8. In an ice-making or refrigerating machine, the combination, with the steam chambers or spaces of the still, of a common supply-pipe, branches therefrom to each steam chamber or space, a common outlet or exhaust 110 pipe, and branches therefrom to each steam chamber or space, substantially as set forth.

9. In an ice-making or refrigerating machine, the combination, with the steam or heating pipes or chambers, of a common supply-pipe, and a common exhaust or outlet pipe, and connections from both to each steam or heating pipe or chamber, whereby the heat and pressure are equalized throughout the still, substantially as set forth. 115

10. In an ice-making or refrigerating machine, the combination, with the dome or stand-pipe and the interceptor, of a branch connection delivering the freed gas into the space surrounding the supply-pipes, substantially as set forth. 120

11. In an ice-making or refrigerating machine, the combination, of the still, the by-pass or shunt-path for delivering the freed gas around the still, the dome or stand-pipe, the interceptor, and the branch connection for delivering the freed gas from the dome or stand-pipe to the exterior chamber of the interceptor, substantially as set forth. 125

12. The combination, in an ice-machine, of an interceptor composed of the interior pipes and the exterior pipes eccentric thereto, with the chambered thimbles on the exterior pipes, 5 containing packings, the glands or thimbles on the interior pipes, having tubular flanges or projections entering the chambered thimbles, and the return bends or elbows connecting the interior pipes for securing tight joints 10 and permitting expansion and contraction of the parts, substantially as described.

13. In an ice-making or refrigerating machine, the combination of the still, the weak-water cooling-chamber 78, and pipe-connections, substantially as shown, for passing the weak or spent water therethrough and partially cooling it on its road to the absorber, 15 substantially as set forth.

14. In an ice-making or refrigerating machine, the combination of an interceptor, a stand-pipe or dome, a still, a condenser, a receiver, an expander and refrigerator, an ab- 20

sorber, and pipe-connections, substantially as set forth.

15. In ice-making or refrigerating machines, 25 the improved method of heating the incoming liquor and cooling the outflowing freed gas, consisting in causing them to flow in opposite directions in contact with each other through the dome or stand-pipe, and out of contact 30 in concentric pipes through the interceptor, substantially as set forth.

16. In an ice-making or refrigerating machine, the combination, with the still, interceptor, expander, and condenser, of the spent 35 or weak water cooling-chamber 78, system of pipes 40, and pipe-connections therefor, substantially as set forth.

In testimony whereof I affix my signature in presence of two witnesses.
